CLAIM

The ornamental design for a bottle, as shown and described.

DESCRIPTION

FIG. 1 is a front elevational view of a bottle according to the present design; the back elevational view, the right side elevational view, and the left side elevational view being the same;

FIG. 2 is a top plan view thereof;

FIG. 3 is a bottom plan view thereof; and,

FIG. 4 is a cross-sectional view taken through line 4—4 of FIG. 2.

The broken line shown in FIGS. 1 and 4 is for illustrative purposes only and forms no part of the claimed design.
